UNITED STATES PATENT OFFICE.

ODAVILLE YATES, SR., OF PORTLAND, OREGON.

GUARD FOR CORDS OR WIRES OF TELEPHONE SETS.

1,164,563.

Specification of Letters Patent.

Patented Dec. 14, 1915.

Application filed July 22, 1914. Serial No. 852,445.

To all whom it may concern:

Be it known that I, ODAVILLE YATES, Sr., a citizen of the United States, residing at Portland, in the county of Multnomah and 5 State of Oregon, have invented new and useful Improvements in Guards for Cords or Wires of Telephone Sets, of which the following is a specification.

This invention relates to improvements 10 in guards or holders for the cords or wires of telephone sets and has particular application to a guard for use in conjunction with portable telephone sets.

In carrying out the present invention, it 15 is my purpose to provide a cord guard or holder whereby the cords leading to the transmitter and receiver will be held to the standard or post of the telephone set in an out of the way position so as to eliminate 20 bunching of the cord beneath the base of the set when the latter is placed on a desk, table or other support.

It is also my purpose to provide a device 25 of the class described which may be readily and quickly applied to the standard or post of the telephone set and removed therefrom and which when in applied position will hold the cords out of the way.

A further object of my invention is to 30 provide a slack take-up device whereby the slack in the cord leading from the bell box of the telephone set to the base of the standard or post will be automatically taken up when the telephone set is not in use and 35 which will permit the cord to be paid out when the telephone set is moved from place to place in the use thereof.

With the above and other objects in view, 40 the invention consists in the construction, combination and arrangement of parts hereinafter set forth in and falling within the scope of the claims.

In the accompanying drawings: Figure 1 45 is a perspective view of a telephone set equipped with a guard and slack take-up device constructed in accordance with the present invention. Fig. 2 is a plan view of the guard showing the same in open position and removed from the telephone set. 50 Fig. 3 is an end view of the guard in closed position. Fig. 4 is a fragmentary perspective view of the guard showing the latch for holding the same closed. Fig. 5 is a perspective view of the slack take-up device 55 distended. Fig. 6 is a cross sectional view therethrough.

Referring now to the drawings in detail, A designates a portable telephone set comprising a standard or post 1 having the lower end thereof secured to the base 2 as usual and the upper end carrying the transmitter 3, and a receiver 4 normally supported by the forked extremity 5 of the arm 6 pivoted to the standard 1 adjacent to the upper extremity thereof.

My improved guard or cord holder is indicated at 7 and, in the present instance, comprises securing bands 8, 9 encircling the standard 1 adjacent to the upper and lower ends thereof respectively and each formed 60 of two sections 10. One end of each section is pivoted to the adjoining extremity of the other section as at 11, while the remaining ends of the sections are extended outwardly as at 12 and spaced apart in parallelism. 70

The space between the outwardly extending portions 12 of the sections 10 of the securing band 8 registers with the space between the outwardly extending portions of the sections 10 of the securing band 9 and disposed within these spaces is a vertical tube 13 comprising longitudinal sections 14, 14 each secured to or formed integral with the adjacent outturned end portions 12 of the securing bands 8 and 9. The inner face of 80 one outturned end portion 12 of each securing band is equipped with an inwardly extending U-shaped strap 15, while the confronting face of the remaining outturned end portion has pivotally connected thereto 90 as at 16 a strip 17 capable of vertical swinging movement and having the bottom edge thereof formed with teeth 18 adapted to interchangeably engage the central portion of the strap 15 to hold the sections 10, 10 of the 95 particular securing band clamped about the standard.

In practice, the guard 7 is opened up as 100 illustrated in Fig. 2 when applying the same to the telephone set, the sections 10 of the securing bands 8 and 9 are swung about the pivots 11 so that the sections encircle the adjacent portions of the post or standard 1 of the telephone set. As the outwardly projecting ends 12 of the sections of the securing band move toward each other the longitudinal sections 14, 14 of the tube 13 engage each other and so form the tube. When 105 the sections 14 are in tube formation the toothed edges of the strips 17 are engaged 110 with the central portions of the straps 15, thereby holding the securing bands clamped

about the standard and the tube 13 in a vertical position parallel with the standard. Previous to the sections of the tube engaging each other, the cords or wires of the telephone set are placed between the sections and held therein when the latter are assembled, as illustrated in Fig. 1 of the drawings. By means of this construction, it will be seen that the cords leading to the 10 transmitter and receiver are held in an out of the way position, thereby preventing bunching of the cord above the base of the telephone set when the latter is placed upon the table or other support. The upper extremity of the tube 13 is preferably curved 15 so as to prevent mutilation of the cords at the upper end of the tube.

In order to take up the slack in the cord connecting the transmitter with the bell box 20 or battery box of the telephone set, I employ a slack take up device, which, in this embodiment of my invention, comprises a helical spring 20 having each coil thereof equipped with a number of hooks 21. This 25 spring is of the contractile type and the particular cord of the telephone set is trained around the coils thereof and held thereto by means of the hooks 21, the convolutions of the cord lying within the coils of the spring. 30 When the telephone set is idle and supported adjacent to the wall, the coils of the helical spring 2 are in normal retracted position thereby taking up the slack in the cord. On the other hand, when the telephone set is 35 pulled away from the wall for use the coils of the spring are distended and the convolutions of the cord of the telephone set similarly affected, thereby lengthening such cord to the necessary length. When the telephone set is replaced the spring 20 reacts 40 and so takes up the slack.

From the foregoing description taken in connection with the accompanying drawings, the construction, mode of operation 45 and manner of employing my invention will be readily apparent. It will be seen that I have provided a guard or holder for the cords of portable telephone sets whereby bunching of the cord beneath the base of 50 the telephone set when the latter is placed upon a stand or table is eliminated. Furthermore, it will be seen that I have provided a slack take-up device whereby the slack in the telephone cord between the instrument and the bell box, or battery box is 55 automatically taken up when the instrument is placed against the wall or other support of the bell box.

While I have herein shown and described one preferred form of my invention by way of illustration, I wish it to be understood that I do not limit or confine myself to the precise details of construction herein described and delineated, as modification and variation may be made within the scope of 65 the claims without departing from the spirit of the invention.

I claim:

1. A guard for portable telephone sets comprising a rigid tube parallel with the vertical standard of the telephone set and through which the wires leading into and out of the base pass, said tube having the upper end thereof disposed in proximity to the upper end of the vertical standard to 75 hold the wires elevated and comprising two longitudinal sections capable of relative movement, and means holding said sections in tube formation and connecting the same to the vertical standard of the telephone set. 80

2. A guard for the cord of portable telephone sets comprising a vertical tube formed of two longitudinal sections and disposed in parallelism with the vertical standard of the telephone set and having the upper end thereof disposed in proximity to the upper extremity of the standard, cords leading into and out of the base of the telephone set being passed through said tube, and sectional securing bands having the sections thereof 85 connected with the sections of said tube respectively to hold the tube to the standard and the sections of the tube in tube formation.

3. A guard for the cord of portable telephone sets comprising a vertical tube formed of two longitudinal sections and disposed in parallelism with the vertical standard of the telephone set and having the upper end thereof disposed in proximity to the upper extremity of the standard, cords leading into and out of the base of the telephone set being passed through said tube, sectional securing bands having the sections thereof 90 connected with the sections of said tube respectively to hold the tube to the standard and the sections of the tube in tube formation, and means carried by the sections of said bands and holding such sections in band formation. 100

In testimony whereof I affix my signature in presence of two witnesses.

ODAVILLE YATES, Sr.
